UNITED STATES PATENT OFFICE.

STEPHEN P. RUGGLES, OF BOSTON, MASSACHUSETTS.

IMPROVEMENT IN VEHICLE-WHEEL HUBS.

Specification forming part of Letters Patent No. **221,976**, dated November 25, 1879; application filed October 13, 1879.

To all whom it may concern:

Be it known that I, STEPHEN P. RUGGLES, of Boston, in the county of Suffolk and State of Massachusetts, have invented certain new and useful Improvements in Vehicle-Wheel Hubs; and I do hereby declare that the following is a full, clear, and exact description of the same, reference being had to the accompanying drawings, making a part of this specification, in which—

Figure 1 represents a perspective view of the hub. Fig. 2 represents a longitudinal section of the same. Fig. 3 represents a front view of the central piece used in forming the hub. Fig. 4 represents an end view of the hub.

My invention relates to vehicle-wheel hubs made of metal, and suitable for children's carriages, velocipedes, and other light vehicles.

Heretofore hubs of this class of vehicles have generally been made of wood, and, being of small size, they cannot resist rough usage or strain, to which they are often subjected. The hubs of wagon-wheels have been made of metal, and are quite strong, the various pieces forming them being securely bolted together. They have been made with a central pipe-box, provided with a plane central flange having recesses, and provided with recessed caps bolted together to secure and retain the spokes; but this construction renders them too cumbersome and expensive to be adopted for light children's carriages.

The object of my invention is to construct a hub of a series of cast-metal pieces, each having indented faces made to interlock with the adjoining one, so as to require but a small additional cohesive power to retain them permanently united, and this cohesive power is obtained by simply dipping the assembled parts in a liquid metallic bath to fill the interstices.

My invention consists in a hub formed by the combination of a series of metal pieces, each having one or both of its faces wavy or formed with projections and indentations adapted to interlock with the adjoining piece.

It consists, also, in a hub formed of distinct metal pieces united together by soldering, galvanizing, or dipping into liquid metal.

It consists, also, in a hub provided with a central bearing formed of two separate pipe-boxes, each surrounded by a chamber open to the air, and independent of the other, to pre-

vent heating of said boxes, as will be herein-after described in connection with the drawings, and pointed out in the claims.

In the drawings, the pipe box made to support the axle is made primarily of two independent castings. The box A forms the inner support of the axle, and is provided with a wavy flange having half-cylindrical, and at the same time radial, recesses *a* to receive the spokes S, as will be hereinafter described, and angular projections *a'* to engage with inversely-made indentations *c'* in a central ring, C. The box B forms the outer support of the axle, and is also provided with a similarly wavy flange having half-cylindrical, but radial, recesses *b* and projections *b'* to engage into indentations *c'* on the opposite side of the central ring, C. This ring is also provided with half-cylindrical recesses *c*, corresponding in size and direction with the recesses *a* and *b* of the boxes, so that when the three pieces A, B, and C are brought together a series of holes are produced in a wavy line upon the circumference of the hub, arranged in the most desirable order to receive the spokes S and produce a strong wheel.

The hub is further improved in construction and design by means of cast-metal caps D and E. Each cap has a central opening in the outer end thereof, made to fit over the end of its pipe-box, and its inner end has such wavy configuration as to fit the outer side of the flange of said pipe-box, forming an air-chamber open to the atmosphere through the openings *d* and *e* to keep the bearings cool. These caps D and E may, if desired, be made of stamped sheet metal.

To still further improve its appearance, the hub is provided with a sheet-metal ring, *f*, and an outer cap, *g*, plated with silver or nickel.

To unite the cast-metal parts of the hub together, the boxes A and B may be slightly riveted to their caps by a few slight blows with a hammer on the outer end of said boxes, or all the pieces A B C and the caps D E united temporarily by a couple of light pieces of wire passing through the central openings and secured on the outside, and in this condition dipped into a bath of melted zinc or other suitable metal, which will fill all the interstices, solder the parts, and complete the hub in an instant. Although this soldering metal appears

to give all the cohesion of parts required for light hubs, bolts may, in addition, be passed through the pieces A B C, adjoining to their rims, and between the spokes, if additional strength is required for heavy hubs.

The openings for the spokes may be of any desired form, and the inner end of the spokes should be made to fit them tightly; and I prefer to form each spoke with a shoulder, s , to rest upon the projecting rim of the hub.

For very light wheels—as for toys—the pieces A B C D E, above mentioned as made of cast metal, may be made of sheet metal, stamped and formed substantially as represented.

The spokes may extend within the hub, so as to rest upon the box A, and the inner end of said box may be prolonged in the interior, so as to support the ends of both series of spokes.

Having now fully described my invention, I claim—

1. In a vehicle-wheel hub, the combination of a series of cast-metal pieces, each having one or both of its faces wavy or formed with side projections and indentations adapted to

interlock with the adjoining piece, substantially as and for the purpose described.

2. A vehicle-wheel hub formed of distinct metal pieces having wavy faces, substantially as shown and described, united together by soldering, galvanizing, or dipping into liquid metal, as and for the purpose set forth.

3. In a vehicle-wheel hub, the combination of a box, A, formed with a wavy flange, a box, B, provided also with a wavy flange, and a central ring, C, having projections adapted to interlock with the flanges of boxes A and B, substantially as and for the purpose described.

4. In a vehicle-wheel hub, the combination of a box, A, formed with a wavy flange and a cap, D, a box, B, provided also with a wavy flange and a cap, E, and a central ring having projections adapted to interlock the flanges of both boxes, with independent air-chambers at each end of the hub, substantially as and for the purpose described.

STEPHEN P. RUGGLES.
